United States Patent Office

Des. 218,288

Patented Aug. 11, 1970

218,288

BEVERAGE CAN

Frederick W. Hilliard, Seattle, and Leslie W. Meyers, Mercer Island, Wash., assignors to Carling Brewing Company Incorporated, Cleveland, Ohio, a corporation of Virginia

Filed Mar. 29, 1968, Ser. No. 11,203

Term of patent 14 years

Int. Cl. D9—07

U.S. Cl. D9—216

FIG. 1 is a front elevation view of a beverage can showing our new design,

FIG. 2 is a top plan view of the beverage can shown in FIG. 1,

FIG. 3 is a bottom plan view of the beverage can shown in FIG. 1.

As the beverage can is circular in all horizontal sections, all side and rear elevation views of the beverage can are identical to FIG. 1.

We claim:

The ornamental design for a beverage can, as shown and described.
